UNITED STATES PATENT OFFICE.

ARVIN R. PAULL, OF UTICA, NEW YORK, ASSIGNOR OF ONE-THIRD TO BENJAMIN J. FISHER AND ONE-THIRD TO WILLIAM F. McCANN, BOTH OF UTICA, NEW YORK.

PULP-SCREENING DEVICE.

Application filed November 1, 1920. Serial No. 420,953.

To all whom it may concern:

Be it known that I, ARVIN R. PAULL, citizen of the United States, residing at Utica, in the county of Oneida and State 5 of New York, have invented new and useful Improvements in Pulp-Screening Devices, of which the following is a specification.

This invention relates to pulp-screening machines, and particularly to certain improvements in machines of this character 10 of the type wherein a rotating cage, provided with peripheral screen plates, is employed for screening the pulp, such as is shown and described in Patent No. 1,149,- 15 534, granted to Arvin R. Paull August 10, 1915.

One object of the present invention is to provide improved means for operating the plunger-plates cooperating with the screen 20 plates to more effectively vibrate the same in order to insure a proper flow of pulp through the screen plates.

Another object of the invention is to provide improved means for mounting the 25 plunger-plates, as well as to improve the construction of the plates and secure more efficient operation of the same.

Another object of the invention is to provide an improved device of this character 30 wherein the rotatable cage is mounted concentric with the cylindrical casing to more efficiently convey the pulp in a circular path along the inner surface of the casing, as well as the provision of suitable means 35 for supplying water to the pulp at proper intervals in its travel to insure thorough screening of the material.

A further object of the invention is to provide improved means for flushing the 40 refuse from the face of the screen after the completion of the screening operation, and to provide means for suitably spraying water upon the outer surface of the screen plates at proper intervals in the operation 45 of the mechanism.

A further object of the invention is to provide a device of this character which is of simple construction and efficient in operation.

50 Further objects of the invention relate to improvements in the various details of construction and methods of operation of the mechanism, whereby the structure will operate more efficiently and by which the 55 capacity of the machine may be varied

to better adapt the same for use under varying conditions of service.

Referring to the drawings,

Fig. 1 is a side elevational view of the machine, certain of the parts being broken 60 away along the line 1—1 of Fig. 2 to better illustrate the operating mechanism and the relative position of the parts;

Fig. 2 is an end elevational view of the machine, with a portion of the outer casing 65 broken away to show the relative positions of the screen plates and plungers cooperating therewith;

Fig. 3 is a top plan view of a portion of one of the screen plates; 70

Fig. 4 is a bottom plan view of a portion of one of the plungers;

Fig. 5 is a detail sectional view taken along the line 5—5 of Fig. 2;

Fig. 6 is a detail view of a portion of one 75 of the end plates;

Fig. 7 is a detail view of a portion of one of the end plates, showing the manner of securing one of the longitudinal tie-bars thereto;

Fig. 8 is a detail view of a portion of one 80 of the end plates, showing the manner of securing the screen plates in place thereon;

Fig. 9 is a longitudinal sectional view of a slightly modified form of the invention; 85 and

Fig. 10 is a transverse sectional view taken substantially along the line 10—10 of Fig. 9.

In the embodiment of the invention shown and described herewith, a substantially cylindrical casing 1 is employed, which is adapted to be supported by means of a plurality of legs 2 arranged in any suitable manner for properly supporting the casing and the mechanism carried thereby. The 90 casing is provided with an inlet passage which is preferably located above the center line thereof and opens into the cylindrical wall of the casing in a direction tangential to the circle defined by a transverse section 95 thereof. The casing is also provided with a manhole 4 located at the top thereof and providing means for obtaining access to the operating mechanism in the interior of the casing. 100

The casing is provided with a pair of end plates 5 and 6 located at opposite ends thereof and extending upwardly and around the inner surface of the casing adjacent to the ends of the cylindrical casing as shown in 110

Figs. 1 and 2 of the drawings. A portion of the upper half of the end plates is open adjacent the center of the casing to permit a view through the upper portion of the casing whereby the operation of the mechanism may be observed. The end plates are each provided with semicircular bearings 7 and 8, respectively, the purpose of which will be more fully described hereinafter, and each end plate has a closed lower portion which terminates substantially on a line with the axis of the casing. An opening 9 is formed in the closed lower portion of the plate 5 through which the screened pulp may pass from the machine through a suitable discharge pipe (not shown). The upper portions of the end plates 5 and 6 are of annular form, as shown in Figs. 1 and 2, and each of the said plates fits closely within and is firmly secured to the ends of the cylindrical casing so as to form, in effect, a portion of the casing.

A cage 10, comprising enlarged central recessed end portions 11 and 12 formed at opposite ends thereof and having a cylindrical sleeve 13 connecting said recessed portions, is mounted for rotation in the semicircular bearings 7 and 8, and semicircular straps 14 and 15 cooperate with the semicircular bearings 7 and 8, respectively, to form bearings for the recessed end portions 11 and 12, respectively, of the cage. Radiating from the enlarged centrally-recessed end portions 11 and 12 is a plurality of spider arms 16 and 17, respectively, which support spiders 18 and 19 adjacent to the end portions of the cylindrical casing. The spiders 18 and 19 are polygonal in form and are provided with bosses 20 extending inwardly towards the center of the casing; and longitudinally-extending tie-bars 21 extend between the spiders 18 and 19 and are connected to the bosses 20 in any suitable manner, as by screws 21, after the manner shown in Fig. 7 of the drawings. The cage thus constituted is concentrically mounted in the casing 1 and is polygonal in cross-section, being provided with a plurality of radial passages 22 the walls of which are formed by the inner faces of the spiders 18 and 19 and the side faces of adjacent longitudinally-extending tie-bars 21, as will be seen upon reference to Fig. 2 of the drawings.

The spiders 18 and 19 are provided with outwardly-extending annular flanges 24 and 25, respectively, the flange 24 cooperating with a similar flange 26 formed upon the end plate 5, and the flange 25 cooperating in a similar manner with a corresponding flange 27 carried by the end plate 6. It will be seen that these cooperating flanges are positioned closely adjacent each other but separated slightly so as not to interfere with the rotation of the cage relative to the casing and the end plates secured thereto. A strap

28 overlies the adjacent edges of the cooperating flanges 24 and 26 and is preferably capable of adjustment whereby it may be drawn sufficiently close against the outer circumferences of these flanges to prevent the pulp from leaking therebetween. A similar strap 29 overlies the cooperating flanges 25 and 27 and is capable of adjustment in a similar manner to permit it to be so tensioned against the outer surfaces of the flanges as to prevent leakage of the pulp therebetween.

A plurality of substantially rectangular screen plates 30 are each secured to the corresponding exterior polygonal faces of the oppositely-positioned spiders 18 and 19 and adjacent longitudinally-extending tie-bars 21, whereby the outer surfaces of the cage 10 presents the appearance of a polygonal prism when the passages 22 are covered by the screen plates 30. Each screen 30 is provided with a plurality of slots 31, the side walls of each slot being inclined inwardly towards each other, whereby the slots are widened as they extend towards the center of the cage to more effectively separate the finer portions of the pulp from the coarse splinters, etc., as shown in Fig. 2 of the drawings.

The longitudinally-extending tie-bars 21 are each provided with inclined outer faces 33 against which the screen plates 30 are adapted to bear when they are positioned upon the adjacent tie-bars and oppositely-located spiders, and the adjacent side edges of adjoining screen plates are secured in position by means of a longitudinally-extending angle-bar 34 provided with oppositely-projecting flanges 35 adapted to overlie the adjacent edges of the adjoining screen plates and clamp them firmly against the inclined outer faces of the longitudinally-extending tie-bars. Each of the angle-bars 34 is secured to the corresponding tie-bar by means of a row of screws 36, or other suitable fastening means, positioned centrally thereof and adapted to pass into the tie-bar to rigidly secure each angle-bar to its corresponding tie-bar and firmly clamp the adjacent edges of adjoining screen plates therebetween. Each of the angle-bars 34 is provided with an outwardly-extending flange 37 extending substantially throughout its length, and a radial fin 38 is suitably secured in any desired manner to each flange 37 and extends outwardly from the cage in a radial direction and into approximate engagement with the inner surface of the casing with which it is substantially in contact as the cage rotates within the casing.

Located in each passageway 22 and radially inward from each screen plate 30 is a plunger 40 substantially coextensive with the corresponding screen plate 30 and adapted to be vibrated during rotation of the cage to

draw the finer portion of the pulp through the screen. A strip of rubber or similar material 41 is secured to the outer edges of the plunger in any suitable manner, as shown in Figs. 1 and 2 of the drawings, and has its outer edge projecting within grooves 42 formed in the inner faces of the spiders 18 and 19 and grooves 43 formed in the side faces of the longitudinally-extending tie-bars 21. The plungers are reciprocated towards and from the screen plates, but the distance which they move is relatively slight and is insufficient to entirely withdraw the edges of the rubber strip from the grooves 42 and 43, thus a seal is provided around the outer edge of each plunger so that the radial passage 22 in which it moves is entirely closed by the plunger and a most efficient suction effect produced upon the screen by reciprocation of the plunger.

Each plunger 40 is provided with one or more openings 45 formed therein and preferably located adjacent to the longitudinal center of the plunger. In the present instance, these openings are three in number and are each of oblong form as shown in Fig. 4. A slide 46, preferably formed of a flexible metal and provided with parallel guide-slots 47, is secured to the inner surface of each plunger 40, where it is retained against accidental removal or displacement by bolts or rivets 48 carried by the plunger and passing through the parallel slots 47, the said bolts or rivets being provided with enlarged heads 49 which overlie a portion of the slide adjacent to the slots 47 and thus hold the slide against accidental removal from the plunger while permitting the same to be moved longitudinally of the plunger to partially cover the openings 45, when desired. The slide is provided with an out-turned handle 50 which may be grasped for moving the slide longitudinally of the plunger to adjust the same in position over the opening 45, and a tooth 51 is provided upon the under surface of the slide 46 for engagement with any one of a plurality of notches 52 formed in the under surface of the plunger 40, whereby the slide may be held in any one of a plurality of adjusted positions in which the openings 45 are closed to any desired extent. Each plunger is provided with a pair of longitudinally-extending ribs 54 and 55, which are connected together near the longitudinal center of the plunger by a baffle-plate 56 which extends transversely of the plunger and is spaced a slight distance therefrom, being located directly opposite the openings 45 formed in the plunger.

Radial stems 58, each of which is provided with a flattened head 59, support opposite ends of each plunger, the flattened heads 59 being secured to the plunger by suitable fastening means 60. The stems 58 are slidably

mounted in radial sleeves 61 carried by the oppositely-positioned recessed end portions 11 and 12 of the cage, and leakage of pulp around the stems is prevented by any suitable means, such as packing 62 and glands 70 75 63. Cam-followers 65 are threaded upon the inner ends of the stems 58, and suitable coiled springs 66 surround the inner ends of the stems 58 and bear against the cam-followers 65 and a portion of the inner surface 75 of the recessed end portions 11 and 12 to normally urge the stems 58 radially inward into retracted position.

A shaft 67 is rotatably mounted in the sleeve 13 forming a part of the cage 10 and is supported for rotation by bearings 68 carried by the recessed end portions of the cage. The shaft 67 is concentrically mounted relative to both the casing and the cage. Cams 70 are rigidly secured to the shaft 67 in position to operatively engage the two sets of cam-followers 65 and actuate the same to force the stems 58 radially outward against the tension of the coiled springs 66. The oppositely-positioned cams 70 are so adjusted as to actuate the stems 58 carried by each plunger simultaneously and thus move both ends of each plunger in unison.

Suitable means is provided for rotating the cage 10 in the bearings 7 and 8 and at the same time rotating the shaft 67 for actuating the stems 58 to vibrate the plungers 40 carried by the cage. The cage is preferably rotated at a considerably lower speed than the shaft 67, whereby the plungers 40 are each vibrated a considerable number of times (preferably from 100 to 200) during each complete revolution of the cage. Any suitable form of driving mechanism may be employed for rotating the shaft 67, such as the usual fast-and-loose pulleys (not shown), and the cage is preferably rotated from the shaft 67 through any suitable form of reduction-gearing, such as that shown for the purpose of illustration in the accompanying drawings.

In the form of reduction-gearing illustrated herewith, a spur-gear 72 is keyed or otherwise rigidly secured to the shaft 67 which meshes with a spur-gear 73 carried by a suitable counter-shaft rotatably supported by a standard 74 and a bracket 75 secured to the casing. A bevel-gear 76 is also fixedly secured to the counter-shaft and meshes with a bevel-gear 77 secured to a shaft 78 rotatably mounted in the bracket 75 and located substantially at right-angles to the counter-shaft mentioned above. The shaft 78 is provided with a worm 79 which is adapted to engage a worm-gear 80 keyed or otherwise firmly secured to the recessed end portion 12 of the cage. It will be obvious that by means of the structure just described the shaft 67 may be rotated at a relatively high speed and through the reduction-gearing rela- 130

tively slow rotative movement may be imparted to the cage. In this way, the cage, together with the series of peripheral screen plates carried thereby and the series of 5 plungers cooperating with the screen plates, may be rotated bodily, while at the same time each plunger is vibrated by the cams 70 acting in opposition to the coiled springs 66 at relatively short intervals as compared 10 with the period of rotation of the cage.

It will be seen from the above description and an inspection of the drawings that the space between the inner cylindrical surface of the casing and the outer surface of the 15 cage is divided into a plurality of longitudinally-extending open-ended compartments by the radial fins 38, which compartments are normally in communication with each other through annular passages 84 and 85 20 at opposite ends of the casing. As the cage rotates in the direction of the arrow A shown in Fig. 2 of the drawings, the fins forming the side walls of these open-ended compartments travel around the interior of 25 the casing, thus tending to cause the greater portion of the pulp to travel in a circular path about the interior of the casing and be screened by having the finer portions thereof drawn through the peripheral screen plates 30 carried by the cage through the continued vibration of the plungers. One or more pipes 86 may be provided to pass through the end plate 6 and communicate with the annular passage 85 for supplying water to 35 the pulp as it is forced around the casing so as to insure a proper fluidity for the pulp to enable it to be efficiently screened. Longitudinally-extending spray-pipes 87 and 88 extend along the upper surface of the casing, each of which pipes is provided with a 40 plurality of downwardly-directed openings communicating with the interior of the casing, whereby a spray of water may be delivered to the outer surfaces of the screen 45 plates at proper points in their travel to add water to the pulp deposited upon the screens and clear the openings in the screen plates of particles of pulp which may be lodged 50 therein.

Located in the end plates 5 and 6 adjacent to the upper portion of the casing and extending above the normal level of the pulp in the casing are inwardly-projecting partitions 90 and 91 arranged substantially 55 flush with the ends of the radial fins 38, as shown in Fig. 1 of the drawings, and extending a sufficient distance circumferentially of the casing to substantially close the normally open end of each of the compartments above mentioned during the latter portion of its travel around the casing. The partition 91 is provided with an oblong opening 93, as shown in dotted lines in 60 Fig. 2, and directly opposite the opening 93 is a water-supply pipe 94 which passes

through the end plate 6 and the partition-plate 90. When each of the above-mentioned open-ended compartments reaches this point in their travel about the casing, practically all of the pulp originally contained in the compartment has been screened and there remains upon the outer surface of the screen a quantity of refuse such as splinters, coarse 70 particles of pulp, etc., which would not pass through the screen. A jet of water flowing through the pipe 94 flushes the surface of the screen, thus cleaning the same and driving the accumulated refuse across the face of the screen and through the opening 93 above described, from whence it passes downwardly through a passage 95 between the partition 91 and the outer surface of the end plate and is discharged from the passage 80 through an opening 96, to which a pipe or other suitable means may be secured to convey the refuse away and discharge the same into a drain. The spray-pipe 88 serves to spray a slight amount of water over the screen just prior to its again becoming immersed in the pulp and thus insure a clear 85 screening surface during the working period of the screen.

In order to vary the capacity of the machine and enable the same to be readily adapted to needs of plants having different capacities, it is proposed to increase the capacity of the machine over that of the standard form by increasing the diameters 90 of the casing and cage to such an extent as to make it possible to place additional screen plates upon the periphery of the cage or to increase the length of the cage and casing, or both increase the diameter and length 100 of the cage and casing to give greater screening surface, as may be found necessary or desirable. In increasing the diameter of the cage and consequently adding to the screening area, it is desirable to increase the number of screen plates by two or multiples of 105 two in order that an even number of screen plates may always be carried by the cage.

The modification illustrated in Figs. 9 and 10 discloses one means which may be employed for arranging and supporting the screen plates upon the cage when the length of the cage is increased to give greater effective screening surface. In this arrangement of the cage mechanism the shaft 67 is mounted concentrically with the cage, as in the form previously described, and spiders 115 18 and 19 are employed for supporting the outer end portions of screen plates 100 and 101, which may be employed instead of a continuous screen plate extending the entire 120 length of the cage and having its ends supported by the spiders 18 and 19. A spider 102 is preferably secured to the sleeve 105 125 midway between the end spiders 18 and 19 and is provided with a plurality of radiating 130

- arms 103, each of which supports the central portion of one of the longitudinally-extending tie-bars 104, which tie-bars are similar in all respects to the tie-bars 21 previously described and serve to support the screen plates 100 and 101 in precisely the same manner as the tie-bars 21 support the screen plate 30. The outer ends of the arms 103 are bolted or otherwise fixedly secured to the inner faces of the longitudinally-extending tie-bars in any suitable manner, and plungers 106 extend between the spiders 18 and 19, the side and end edges of which are connected to the side faces of the tie-bars and end spiders by strips 107 formed of rubber or other flexible material in the same manner as illustrated above in connection with the structure shown in Figs. 1 and 2. Each of the plungers is provided with stems 108 secured to its inner surface at opposite ends thereof, which stems are adapted to be actuated in the manner previously described for vibrating the plungers during the rotation of the cage. In fact, the structure shown in Figs. 9 and 10 is similar in all respects to that previously described, except that the longitudinally-extending tie-bars as well as the plungers are made of considerably greater length in order to lengthen the cage the desired amount and the central spider 102 is therefore employed to provide an additional support for the tie-bars. As stated, the screen plates may also be divided so that two screen plates are employed for covering each of the polygonal faces of the cage, the two screen plates thus employed having their meeting edges arranged adjacent the spider 102, as shown in Fig. 9 of the drawings.
- From the above description it will be seen that as the pulp enters the space between the cylindrical casing and the exterior surface of the cage through the inlet 3, it is engaged by the fins mounted upon the outer surface of the cage and carried around the interior of the casing in the open-ended compartments above mentioned. During the progress of the pulp along the interior surface of the casing, the plungers are constantly vibrated, whereby the finer portions of the pulp are drawn through the screen plates into the radial passages 22 between the screen plates and plungers, from which it flows inwardly through the openings 45 formed in the plungers into the interior of the cage. When the level of the finer pulp in the interior of the cage rises above the level of the opening 9 formed in the cover-plate 5, it flows therethrough into a suitable pipe or receptacle provided for the purpose.
- Leakage of the unscreened pulp around the casing or into the interior of the cage is prevented by the straps 28 and 29 positioned over the cooperating flanges carried by the cage and casing, respectively. As the cage
- continues to revolve, water is sprayed upon the outer surfaces of the screen plates through the spray pipes 87 and 88, and the refuse is flushed by discharge of water from pipe 94 from the surface of each screen plate into the opening 93, thus removing the coarser parts of the pulp before the screen plate again becomes immersed in the pulp contained in the casing. The recessed end portions 11 and 12 are so formed as to permit of ready access to the cam-followers, whereby they may be adjusted to give the requisite throw to the plungers, as well as to permit the coiled springs to be readily removed and replaced, if necessary.
- While the present embodiment of the invention has been described with considerable particularity in order to make it clear to those skilled in the art the precise details of construction which may be employed in its use, it is to be understood that the invention is not limited to the precise details of construction shown and described, or any of them, except as they may be set forth in the following claims.
- What I claim is—
1. In a pulp-screening machine, a cylindrical casing, a cage concentrically mounted for rotation in said casing and provided with a plurality of peripheral screen plates, a reciprocable plunger cooperating with each screen plate, means for rotating the cage, and means for reciprocating the plungers during the rotation of said cage.
  2. In a pulp-screening machine, a substantially cylindrical casing, a cage concentrically mounted for rotation in said casing and provided with a plurality of peripheral screen plates, and a plurality of radial fins carried by said cage, and projecting outwardly therefrom and constantly engaging the inner peripheral surface of the cylinder during rotation of the cage.
  3. In a pulp screening machine a substantially cylindrical casing, a screening cage concentrically mounted for rotation in said casing, a plurality of radial fins carried by said cage and projecting outward therefrom and constantly engaging the inner peripheral surface of the cylinder during rotation of the cage, an inlet for pulp opening into the cylindrical wall of the casing and means for supplying additional water to the pulp in the chambers between adjacent fins as it moves in a circular path along the interior of the casing.
  4. In a pulp-screening machine, a substantially cylindrical casing, and a screening cage concentrically mounted for rotation in said casing and provided with radial fins mounted for substantial engagement with the interior surface of the casing throughout its extent for conveying the pulp there-around.
  5. In a pulp-screening machine, a substan-

5 substantially cylindrical casing, a screening cage concentrically mounted for rotation in said casing and provided with radial fins mounted for substantial engagement with the interior surface of the casing during the entire rotation of the cage and dividing the annular space between the cage and casing into a plurality of open-ended compartments communicating with each other through annular passages provided at the ends of the casing.

6. In a pulp-screening machine, a substantially cylindrical casing, a screening cage concentrically mounted for rotation in said 15 casing and provided with radial fins mounted for substantial engagement with the interior surface of the casing during the entire rotation of the cage and dividing the annular space between the cage and casing into a plurality of open-ended compartments 20 communicating with each other through annular passages provided at the ends of the casing, and means for exerting suction upon portions of the cage to screen pulp there- 25 through.

7. In a pulp-screening machine, a substantially cylindrical casing, and a cage concentrically mounted for rotation in said casing and provided with a plurality of 30 screen plates located in the periphery thereof and separated from each other by radial fins carried by said cage and mounted for substantial engagement with the interior surface of the casing during the entire rotation of the cage and dividing the annular space between the cage and casing into a plurality of open-ended compartments communicating with each other through annular 35 passages provided at the ends of the casing.

40 8. In a pulp-screening machine, a substantially cylindrical casing, a cage concentrically mounted for rotation in said casing and provided with a plurality of screen plates located in the periphery thereof 45 and separated from each other by radial fins carried by said cage, said fins being mounted for substantial engagement with the interior surface of the casing during the entire rotation of the cage and dividing the 50 annular space between the cage and casing into a plurality of open-ended compartments communicating with each other through annular 55 passages provided at the ends of the casing, and means for exerting suction upon said screen plates to draw pulp there- through.

9. In a pulp-screening machine, a substantially cylindrical casing, a cage concentrically mounted for rotation in said casing and provided with a plurality of screen plates located in the periphery thereof and separated from each other by radial fins carried by said cage, said fins being mounted for substantial engagement with the interior

5 surface of the casing during the entire rotation of the cage and dividing the annular space between the cage and casing into a plurality of open-ended compartments communicating with each other through annular 10 passages provided at the ends of the casing, and reciprocable plungers cooperating with each screen plate to exert suction thereon and draw pulp therethrough.

10. In a pulp-screening machine, a substantially cylindrical casing, a cage concentrically mounted for rotation in said casing and provided with a plurality of screen plates located in the periphery thereof and separated from each other by radial fins carried by said cage, said fins being mounted 75 for substantial engagement with the interior surface of the casing during the entire rotation of the cage and dividing the annular space between the cage and casing into a plurality of open-ended compartments communicating with each other through annular 80 passages provided at the ends of the casing, means for isolating each compartment during a portion of its travel, and means for flushing the screen plate in each 85 compartment during its period of isolation to remove refuse therefrom.

11. In a pulp-screening machine, a substantially cylindrical casing, a screening cage concentrically mounted for rotation within the casing and provided with a plurality of screen plates located in the periphery thereof, radial fins carried by the cage and mounted for substantial engagement with the inner surface of the casing throughout its extent, means carried by the casing and cooperating with the fins for isolating each screen plate during a portion 100 of its movement, and means for flushing the screen plate when it is isolated from the remaining portion of the casing.

12. In a pulp-screening machine, a substantially cylindrical casing, a shaft mounted for rotation within said casing in coincidence with the axis thereof, a cage 110 rotatably mounted upon said shaft and provided with a plurality of screen plates mounted upon the periphery thereof, a plurality of plungers carried by said cage and cooperating with said screen plates, cam means carried by said shaft adjacent the opposite ends of said cage, and means connecting said cam means with the opposite ends of said plungers for simultaneously and intermittently vibrating the opposite 115 ends of said respective plungers.

13. In a pulp-screening machine, a cylindrical casing, a cage rotatably mounted in said casing and provided with a plurality of peripheral screen plates, a plurality of plungers carried by said cage and cooperating with said screen plates, a shaft supported by said casing and provided with

- cam means outside the opposite ends of said cage and means operatively connecting the said cams to the opposite ends of each plunger within the cage for vibrating the 5 plungers during rotation of said cage.
14. In a pulp-screening machine, a casing, a cage rotatably mounted in said casing and provided with plates and longitudinal ribs for dividing the peripheral surface of the 10 cage into radially-extending passages, a screen-plate secured to the cage over each of said passages, a plunger mounted in each passage and having its edges connected with the side walls of the passages by substantially liquid-tight joints, and means for reciprocating said plungers.
15. In a pulp-screening machine, a casing, a cage rotatably mounted in said casing and provided with a plurality of radial passages 20 formed in the periphery thereof and separated from each other by longitudinally-extending ribs, a screen plate secured to the cage over each of said passages, a plunger mounted for reciprocation in each of said 25 passages and a flexible member secured to the edge of each plunger and engaging slots formed in the walls of the corresponding passage.
16. In a pulp-screening machine, a casing, 30 a cage rotatably mounted in said casing, a plurality of screen plates carried by said cage, a plurality of plungers carried by said cage and cooperating with said screen plates, means carried by the cage adjacent the opposite ends thereof and operatively connected with the opposite ends of said respective plungers for reciprocating both ends of each plunger simultaneously and 35 equally and a shaft rotatably supported by said casing and provided with means adjacent the opposite ends thereof for actuating said plunger-operating means.
17. In a pulp-screening machine, a casing, 40 a cage rotatably mounted in said casing and provided with centrally and inwardly recessed end portions, a plurality of screen plates carried by said cage, a plurality of plungers carried by said cage and cooperating with said screen plates, a shaft rotatably supported by said casing concentric with 45 said cage, means carried by the cage and located at opposite ends thereof for operating said plungers, and means located within the recesses of the end portions and on the outer sides thereof for actuating the 50 plunger-operating means upon rotation of said shaft.
18. In a pulp-screening machine, a screen 55 plate, a plunger-plate cooperating therewith and provided with an opening formed therein, and means for regulating the effective size of said opening.
19. In a pulp-screening machine, a screen 60 plate, a plunger-plate cooperating therewith and provided with an opening formed there-
- in, and a slide carried by said plate and adjustable to vary the effective size of said opening.
20. In a pulp-screening machine, a screen 70 plate, a plunger cooperating therewith and provided with an opening, and a baffle located adjacent to said opening and spaced therefrom.
21. In a pulp-screening machine, a screen 75 plate, a plunger cooperating with said screen and provided with an opening formed therein, means for regulating the effective size of said opening, and a baffle located adjacent said opening and spaced therefrom.
22. In a pulp-screening machine, a casing, 80 a cage rotatably mounted in said casing, a series of screen plates carried by said cage, a series of plungers cooperating with said screen plates and each provided with an opening formed therein, and means for sealing the edges of the plungers to insure proper cooperation of the plungers with the 85 screens.
23. In a pulp-screening machine, a casing, 90 a cage rotatably mounted in the casing and provided with a plurality of screen plates, tie-bars extending longitudinally of the cage, and longitudinally-extending angle-bars extending in a direction substantially parallel to that of the tie-bars and adapted to be secured thereto to clamp adjacent edges of the screen plates against the outer faces of the tie-bars and hold them in position 95 thereagainst.
24. In a pulp-screening machine, a casing, 100 a cage rotatably mounted therein and provided with a plurality of screen-plates carried upon the outer surface thereof, and a plurality of angle-bars extending longitudinally of said cage and adapted to secure the adjacent edges of the screen plates thereto, each of said angle-bars being provided with a fin projecting outwardly radially from the outer surface of the cage and into 105 substantial engagement with the inner surface of the casing.
25. In a pulp-screening machine, a substantially cylindrical casing, a cage concentrically mounted for rotation in said casing 115 and provided with a plurality of peripheral screen plates, a reciprocable plunger cooperating with each screen plate, means for rotating the cage, means for reciprocating the plungers during the rotation of said cage and a plurality of radial fins carried by said cage and projecting outwardly therefrom into substantial engagement with the inner peripheral surface of the cylinder 120 during its entire rotation of the cage.
26. In a pulp-screening machine, a substantially cylindrical casing, a screening cage concentrically mounted for rotation in said casing and provided with radial fins mounted for substantial engagement with the interior surface of the casir during the

entire rotation of the cage and means for exerting suction upon portions of the cage to screen pulp therethrough.

27. In a pulp-screening machine, a substantially cylindrical casing, and a cage concentrically mounted for rotation in said casing and provided with a plurality of screen plates located in the periphery thereof and separated from each other by radial fins carried by said cage and mounted for substantial engagement with the interior surface of the casing during the entire rotation of the cage.

28. In a pulp-screening machine, a substantially cylindrical casing, a cage concentrically mounted for rotation in said casing and provided with a plurality of screen plates located in the periphery thereof and separated from each other by radial fins carried by said cage and mounted for substantial engagement with the interior surface of the casing during the entire rotation of the cage and means for exerting suction upon the interior surface of the casing during the entire rotation of the cage.

29. In a pulp-screening machine, a substantially cylindrical casing, a cage concentrically mounted for rotation in said casing and provided with a plurality of screen plates located in the periphery thereof and separated from each other by radial fins carried by said cage and mounted for substantial engagement with the interior surface of the casing during the entire rotation of the cage.

rotation of the cage and reciprocable plungers cooperating with each screen plate to exert suction thereon and draw pulp therethrough. 35

30. In a pulp-screening machine, a substantially cylindrical casing, a cage concentrically mounted for rotation in said casing and provided with a plurality of screen plates located in the periphery thereof and separated from each other by radial fins carried by said cage, said fins being mounted 40 for substantial engagement with the interior surface of the casing during the entire rotation of the cage, means for isolating each compartment during a portion of its travel, and means for flushing the screen 45 plate in each compartment during its period of isolation to remove refuse therefrom.

31. In a pulp-screening machine, a casing, a cage rotatably mounted in said casing and provided with a plurality of radial passages 50 formed in the periphery thereof and separated from each other by longitudinally-extending ribs, a screen plate secured to the cage over each of said passages, a plunger mounted for reciprocation in each of said 55 passages and a flexible member secured to the edge of each plunger and engaging the walls of the corresponding passage by a substantially liquid-tight joint.

In testimony whereof I have affixed my 60 signature.

ARVIN R. PAULL.
